[57] CLAIM

The ornamental design for a terrarium for plants, as shown and described.

DESCRIPTION

FIG. 1 is a front elevation view of a terrarium for plants showing my design, the rear view being substantially the same; and

FIG. 2 is a front elevation view of a further embodiment of a terrarium for plants showing my new design, the rear view being substantially the same.

The bottle member is hexagonal in shape. The rib pattern on the cap member is uniformly spaced around the circumference of the cap member.
